ACCOUNTING MACHINE

Charles L. Lee, deceased, late of Dayton, Ohio,
by Leefe Jane Lee, executrix, Dayton, Ohio, as-
signor to The National Cash Register Com-
pany, Dayton, Ohio, a corporation of Maryland

Original application October 14, 1935, Serial No.
44,838. Divided and this application July 22,
1936, Serial No. 91,877

6 Claims. (Cl. 235—60)

This invention relates to bookkeeping or ac-
counting machines and the like, but more par-
ticularly to improvements in the operating and
controlling mechanisms of machines of the type
5 illustrated and described in Letters Patent of
the United States Nos. 1,197,276 and 1,197,278,
issued September 5, 1916, to Halcolm Ellis and
United States Patent No. 1,819,084, issued Au-
gust 18, 1913, to Emil John Ens. This case is a
10 division of applicant's pending application Serial
No. 44,838 filed October 14, 1935.

Practically all the electrically operated adding
and listing machines, commonly referred to as
bookkeeping or accounting machines, of today
15 have evolved from a hand-operated machine.
Most of the earlier machines were equipped with
a hand lever which operated an oscillating drive
shaft which in turn actuated the mechanism of
the machine. Later, these machines were
20 equipped with electric motors which oscillated
the drive shaft in substantially the same manner
as the hand lever. In this transition the electric
motors were merely added to the hand-operated
machines and in most cases no attempt was
25 made to modernize or improve the operating
and actuating mechanisms of the machine.

The various advantages of the revolving drive
shaft over the oscillating drive shaft will be re-
vealed as the specification progresses.

30 It is, therefore, an object of this invention to
provide accounting machines of the type re-
ferred to above with a revolving drive shaft.

Another object is to provide novel controlling
means for the rotary drive shaft mechanism.

35 Still another object is to adapt the overdraft
device for use with the rotary drive shaft mecha-
nism.

A further object is to supply an improved key
releasing means.

40 A still further object is to provide novel means
to select and condition the different totalizers
for their various functions.

A still further object of this invention is the
provision of novel means to control the machine
45 releasing means in certain operations.

Another object is the provision of novel mech-
anism for controlling the machine releasing
means during overdraft operations.

Another object of this invention is the novel
50 mechanism for transposing complementary
amounts to print the true negative total in a
machine of this type having a rotary drive shaft.

With these and incidental objects in view, the
invention includes certain novel features of con-
55 struction and combination of parts, the essen-

tial elements of which are set forth in appended
claims and a preferred form or embodiment of
which is hereinafter described with reference to
the drawings which accompany and form a part
of this specification. 5

izer controlling mechanism and the machine re-
leasing mechanism.

GENERAL DESCRIPTION

50

The machine of the present invention is of the
well known Ellis type and is equipped with a
laterally shiftable traveling carriage supporting
a platen roll adapted to present record material
to the type carriers. Depending upon the use to 55

which the machine is to be put, it may or may not be equipped with a typewriter keyboard and type for the entering of various data upon the record material. The machine of the present invention is equipped with a rotary drive shaft, which replaces the conventional oscillating drive shaft used heretofore in machines of this type. A constantly running motor is operatively connected to the drive shaft by means of a clutch mechanism which is controlled by the usual releasing mechanism. In all operations except overdraft operations, depressing the regular release bar causes the motor to turn the drive shaft one revolution to operate the machine through one cycle of movement. In overdraft operations, depressing the overdraft key causes the drive shaft to make three revolutions to operate the machine through three cycles of movement to transpose the complement of an overdraft into a true negative amount and print this amount on the record material carried by the platen roll.

The present machine is equipped with four totalizers, one of which is an adding and subtracting or balance totalizer, the others are straight adding totalizers. The totalizers are actuated by a plurality of denominational reciprocating racks which are in turn positioned in adding and subtracting operations under control of a plurality of amount keys arranged in denominational rows on the keyboard. In total-taking operations, the totalizer wheels position the racks to record the amount on said totalizer wheels. There is a type carrier for each denomination and they are positioned by the actuator racks commensurate with the value of the depressed amount keys or the amount on the totalizer wheels.

The adding and subtracting functions of the present machine are controlled by the traveling carriage in tabulated positions thereof and the other functions, including non-add, sub-total, total, repeat, and also subtract, are governed by a row of control keys located on the left side of the keyboard. Other features of the instant machine will be disclosed in the detailed description following.

DETAILED DESCRIPTION

Framework and operating mechanism

The framework of the machine is supported by a right frame 40 (Figs. 1, 2, and 16) and a left frame 41, secured to a machine base 42, which also supports a suitable cabinet or case (not shown) which encloses the mechanism of the machine. Mounted on the machine case is a laterally shiftable traveling carriage (not shown) similar to that used on typewriters, supporting a platen roll 43 (Fig. 12) which carries record material in proper relation to the type carriers, one of which, an amount segment 44, is here shown. Secured to the base 42 is an electric motor 45 (Figs. 1, 3, and 4) of the constantly running type, geared to a clutch driving member 46 adapted to be frictionally connected to a clutch driven member 47, both of said clutch members being rotatably supported by a stud 48 secured in the motor frame. Secured to a hub of the clutch driven member 47 is a gear 49 connected by an intermediate gear 50 loose on a stud 51 in the motor frame to a gear 52 secured on a main drive shaft 53, opposite ends of which are journaled in the frames 40 and 41.

One end of a clutch band 54 (Fig. 3) is secured to the clutch driven member 47, while the other end thereof is connected to a bell crank 55 loose

on a stud 56 in the member 47 and adjustably connected to an arm 57 also loose on the stud 56. The upper end of the arm 57 cooperates with a bentover ear 58 of a lever 59 loose on a stud 60 in the motor frame. An upward extension of the lever 59 is connected by a link 61 to an arm 62 loose on an auxiliary differential engaging shaft 63 journaled in the frames 40 and 41. The arm 62 has a step 64 adapted to cooperate with a stud 65 in one arm of a three-armed lever 66 loose on a stud 67 in the frame 40. An upwardly extending arm of the lever 66 is bifurcated to embrace a stud 68 in a release plate 69 pivoted on a stud 70 in the frame 40. The plate 69 has a stud 71 straddled by the bifurcated lower end of a stem 72 of a starting bar 73 slidably supported by an auxiliary keyboard plate 90. Another stem 74 of the bar 73 is loosely connected by a stud 75 to a rearwardly disposed arm of the lever 66. A spring 76 urges the plate 69 clockwise and the lever 66 counter-clockwise to normally maintain the stud 65 in the path of the step 64. Depressing the starting bar 73 rocks the plate 69 counter-clockwise and the lever 66 clockwise to move the stud 65 out of the path of the step 64. This allows a torsion spring 77 (Fig. 3) to rock the lever 59 counter-clockwise to move the ear 58 out of the path of the upper end of the arm 57. A spring 78 then urges the arm 57 and the crank 55 counter-clockwise to expand the band 54, thereby causing it to grip the inner surface of the constantly revolving clutch driving member 46.

In all machine operations except overdraft operations, the clutch driven member 47, the gear 52, and the main drive shaft 53 make one counter-clockwise revolution. Near the end of rotation of the shaft 53, a stud 79 in the gear 50 engages an ear 80 of the lever 59 to rock said lever clockwise. Consequent clockwise movement of the arm 62 moves the step 64 beyond the stud 65, allowing the spring 76 to restore the lever 66 to normal position, so that the stud 65 retains the plate 62 and lever 59 in untripped position. Return movement of the lever 59 moves the ear 58 in the path of the arm 57, which, upon engagement therewith, disengages the clutch driven member from the clutch driving member.

Loose on a stud 81 (Fig. 1) in the motor frame is a return lever 82 urged clockwise by a spring 83 tensioned between said lever and a stud 84. The upper end of the lever 82 has therein a camming notch, which, in cooperation with a roller 85 carried by the gear 49, completes return movement of the machine operating mechanism to home position after the clutch is disengaged as related above. An extension 86 of the lever 82, in cooperation with the stud 84, limits clockwise movement of said lever when the roller 85 moves out of engagement therewith.

Referring to Fig. 3, a simple and efficient device is provided to prevent repeat operations of the machine in case the starting bar 73 is retained depressed. This mechanism includes a non-repeat latch 87 loose on the shaft 67. Said latch 87 is urged clockwise and normally maintained in contact with a stop stud 88 in the lever 66 by a spring 89. Clockwise releasing movement of the lever 66 moves a hook 93 of the latch 87 into the path of a similar hook 94 on the arm 62. In case the starting bar 73 is retained depressed during the restoration of the arm 62, the hook 93 latches over the hook 94 when hook 94 is restored by stud 79 engaging the ear 80, and prevents a repeat operation of the machine by retaining said arm 62 and the lever 59 in untripped position. As

soon as pressure is removed from the bar 73, the lever 66 is restored counter-clockwise by the spring 76, which disengages the hook 93 from the hook 94 and causes the stud 65 to reengage the step 64. A brace plate 95 (Fig. 1) supports the right-hand ends of the studs 48, 51, and 81.

Referring to Fig. 2, secured on the main drive shaft 53 are companion cams 96 and 97, the peripheries of which are adapted to cooperate with rollers (only one shown) carried by a Y-shaped lever 100 loose on a stud in the frame 40. The lever 100 has a stud 102 which extends through a slot 103 in an arm 104 secured to a leading frame shaft 105 journaled in the frames 40 and 41. During each machine operation, the cams 96 and 97, by means of the lever 100, oscillate the arm 104 and the shaft 105 first counter-clockwise and then back to normal position through an approximate angle of 40 degrees.

Shown in Fig. 11 is the means for operating the printer mechanism. Secured on the main drive shaft 53 are companion cams 106 and 107 cooperating respectively with rollers 108 and 109 carried by a cam arm 110 loose on the stud 101. The arm 110 has a stud 111 adapted to cooperate with a notch in a link 112, the upper end of which is connected to an arm 113 resiliently connected by a spring 114 to an arm 115 secured on a printer shaft 116 journaled in the frame 40 and in the printer frame (not shown). The notch in the link 112 is constantly engaged with the stud 111 except in overdraft operations, and the manner in which said link 112 functions in overdraft operations will be described later herein. Counter-clockwise revolution of the shaft 53, by means of the cams 106 and 107, the arm 109, link 112, and arms 113 and 115, oscillates the printer shaft 116 first clockwise and then back to normal position to cause the printing mechanism to function.

40 Totalizer and printer actuating mechanism

Fig. 12 illustrates the totalizer and printer actuating mechanism for one denominational unit of the machine. As this mechanism is substantially duplicated in each denominational unit, it is felt that the description of the one unit here shown will be sufficient for the purpose of this specification.

An actuator leading frame 117 is formed by means of two depending arms secured at opposite ends of the shaft 105 connected by a cross-bar or bail 118. Loose on the shaft 105 is a printer reducing segment 119, a downward extension of which is maintained in contact with the leading frame bail 118 by a spring 120 stretched between said reducing arm and said bail. The segment 119 carries a stud 121 embraced by a vertical slot in an actuator rack 122 mounted for horizontal reciprocating movement by means of a grooved rod 123 and a bar 124 cooperating with the rearwardly disposed bifurcated end of said rack 122. The rod 123 and the bar 124 are supported by the frames 40 and 41. The rack 122 has a series of graduated steps 125 which cooperate with corresponding square studs 126 secured in the stems of amount keys 127, the upper ends of which extend through apertures in a keyboard plate 128. Each key 127 has a spring 129 tensioned to urge said keys upwardly. When no amount key is depressed, the rack 122 is retained in zero position by means of a zero stop pawl (not shown).

An arm 130 of the segment 119 is connected by a link 131 to the printer segment 44, which is pivotally connected to an arm 133 rotatably supported by the shaft 116. Loosely connected to

the arm 133 is an anti-rebound plate 134 which cooperates with an anti-rebound pawl 135 connected by a spring 136 to a printer yoke 137 loose on the shaft 116. The plate 134 has a plurality of projections, one of which cooperates with a zero elimination pawl 138 pivoted on a rod supported by the printer frame and having an arcuate tail 143 which cooperates with a stud 144 in a forwardly extending arm of the segment 130. Each pawl 138 has a bent-over lug 145 which overlies its higher order neighbor. Another projection of the plate 134 is engaged by a printer release trigger 146 rotatably supported in the printer frame.

Depressing one of the amount keys 127 releases the zero stop pawl for its related rack 122 and moves the stud 126 of the depressed key into the path of the corresponding step 125 on said rack 122. Initial movement counter-clockwise of the shaft 105 and the leading frame 117, by means of the spring 120, moves the segment 119 and the rack 122 in unison therewith. Rearward movement of the rack 122 is halted when the step 125 engages the stud 126 of the depressed amount key. However, the leading frame 117 completes its cycle of movement, stretching the spring 120. This positions the actuator rack commensurate with the value of the depressed key, and the segment 119, by means of the link 131, positions the type carrier 44 accordingly. When the segment 119 moves away from zero position, the stud 144, in cooperation with the arcuate tail 143, rocks the zero elimination pawl 138 counter-clockwise against the tension of a spring 91 to allow printing movement of the plate 134, arm 133, and type carrier 44. The pawl 138, by means of the overlying ear 145, disengages all the lower order zero elimination pawls from their corresponding plates 134, so that the zeros will print in the lower denomination. When the leading frame 117 reaches the terminus of its initial movement counter-clockwise, the printer release trigger 146 is rocked counter-clockwise, by mechanism not shown, to release the plate 134 and the arm 133 to the action of the spring 136, which has been further tensioned by clockwise movement of the yoke 137. This causes the type carriers 44 to engage the conventional inking ribbon and carry it into contact with the record material carried by the platen roll 43 to record the value of the depressed key.

After impression is completed, return movement clockwise of the leading frame 117 returns the segment 119, the rack 122, and the type carrier 44 to zero position, and return movement counter-clockwise of the yoke 137, by means of a rod 147 supported thereby, restores the plate 134 and the arm 133 to zero position, as shown in Fig. 12.

Secured on the shaft 53 (Fig. 13) are companion cams 148 and 149 cooperating respectively with rollers 150 and 151 carried by a cam arm 152 flexibly connected by a spring 153 to the left arm of a two-armed aliner frame 154, both of said arms of said two-armed aliner frame 154 being secured to a shaft 155 journaled in the frames 40 and 41. After the rack 122, the segment 119, and the type carrier 44 have been positioned in the manner explained above, the cams 148 and 149 rock the frame 154 clockwise to cause an alining bar 156 carried thereby to engage the proper tooth space in the segment 119 to position said segment and the type carrier 44 during impression. Immediately after an im-

pression has been made, the aliner bar 156 is rocked out of engagement with the segment 119.

Totalizers

5 The machine of this invention is equipped with four totalizers (Fig. 12) numbered from 1 to 4 in the customary manner. The upper front or #1 totalizer is an adding and subtracting or balance totalizer, and the other three totalizers are adding totalizers.

10 In adding operations, after the rack 122 has been positioned as explained above, the corresponding wheel of the selected totalizer is rocked into engagement with one of the two sets of teeth carried by said rack, or one of two sets of teeth carried by an extension 139 of the rack 122. Return movement forwardly of the rack 122 rotates the wheel of the engaged totalizer commensurate with the value of the depressed amount key to add this amount therein.

15 In subtracting operations, the corresponding wheel of the No. 1 or balance totalizer is rocked into engagement with the rack 122 prior to its initial movement rearwardly, which movement rotates said wheel reversely to subtract the value of the depressed amount key therefrom. Each of the totalizer wheels carries a transfer cam 140, which, when a totalizer wheel passes through zero, engages and trips an add pawl 141 for the 20 next higher denomination, thereby causing one to be added in said denomination. Likewise, in subtract operations, when a wheel of the No. 1 totalizer is rotated reversely to zero, the transfer cam 140 therefor engages and trips a subtract transfer pawl 142 to cause one to be subtracted from the next higher denomination.

25 In total taking operations, the corresponding wheel of the selected totalizer is engaged with the rack 122 prior to its initial movement rearwardly, which movement rotates said wheel in a reverse direction until said wheel is stopped in zero position by one of the teeth of the transfer cam 140 engaging the inner surface of its add transfer pawl 141. This positions the rack 122 and the type carrier 44 commensurate with the 30 amount on the totalizer wheel. The difference between a read and a reset total taking operation is that in read operations the wheel of the selected totalizer remains in engagement with the rack 122 during its return movement forwardly and is therefore returned to its former position, and in reset operations the wheel of the selected totalizer is disengaged from the rack 122 before said rack starts its return movement 35 forwardly, thereby leaving said wheel standing at zero.

Rack retaining mechanism

40 Mechanism is provided to take the strain off of the actuator racks in total taking operations due to the excessive tensioning of the springs 120 (Fig. 12) when said racks are stopped in one of their earlier positions by means of the transfer cams 140 in cooperation with the transfer pawls 141 when there is a small amount on the totalizer. This mechanism likewise insures that the racks are returned fully to zero at the 45 end of machine operation.

45 At the beginning of machine operation, the 70 rack retaining mechanism is moved to ineffective position. After the leading frame 117 has completed its initial movement counter-clockwise and the rack 122 has been positioned as explained above, the rack retaining mechanism is 75 moved to effective position to relieve the excessive

strain on the rack and totalizer transfer mechanism during return movement of the leading frame 117. This mechanism will now be described in detail.

5 Referring to Fig. 12, each of the racks 122 has on the lower edge thereof a series of ratchet teeth 157 adapted to cooperate with spring pawls 158 secured on a retaining pawl plate 159 rotatably supported by trunnions 160 in the frames 40 and 41. Secured to the plate 159 is a cam 10 arm 161 with a roller 162 which is maintained in contact with the periphery of a plate cam 163, secured on the main shaft 53 by a spring, shown in the parent case but not shown herein, which is tensioned to urge the plate 159 in a 15 clockwise direction.

At the beginning of machine operation the cam 163 rocks the plate 159 counter-clockwise to disengage the pawls 158 from the ratchet teeth 157. After the leading frame 117 has completed its 20 initial movement counter-clockwise and the racks 122 have been positioned by means of the transfer cams 140 in cooperation with the transfer pawls 141 as explained earlier herein for total taking operations, the cam 163 returns the plate 25 159 clockwise to reengage the pawls 158 with the teeth 157. The plate 159 remains in this position throughout the remainder of machine operation, return movement of the racks 122 causing the teeth 157 to ratchet over the pawls 158. 30 This mechanism relieves the transfer mechanism of the strain caused by the springs 120 when the actuator racks 122 are stopped early in their initial movement rearwardly. This mechanism also insures that the racks are returned fully to 35 zero position at the end of machine operation.

Totalizer selecting and controlling mechanism

The adding functions of the different totalizers are controlled by means of control elements located in columnar positions on the traveling carriage in cooperation with hanging bar levers. The subtract function of the No. 1 or balance totalizer is controlled either by control elements on the traveling carriage or by means of a "Subtract" 45 control key. A "Non-add" control key is provided to prevent addition in any of the totalizers when it is desired to record an amount or item without having said amount or item entered in a totalizer. The total taking functions of the present machine are controlled by means of "Total" and "Sub-total" control keys. Adding and subtracting operations may be repeated by means of a "Repeat" control key and an "Error" key is provided to release depressed amount and control 55 keys.

Inasmuch as the totalizer selecting and controlling mechanism is substantially duplicated for each totalizer, it is felt that the explanation of this mechanism in connection with one totalizer will be sufficient. Due to the manner in which the mechanism is illustrated, the functioning of the controlling mechanism in adding and total taking operations will be explained in connection with the lower rear or No. 4 totalizer and in subtracting operations the controlling mechanism will necessarily be explained in connection with the No. 1 or balance totalizer.

Overdraft mechanism

In the present machine, overdraft operations are controlled by means of an "Overdraft" key 408 (Figs. 1 and 2). The "Overdraft" key is normally locked against depression. However, when an overdraft occurs in the balance totalizer, the 75

"Overdraft" key is unlocked and the No. 1 "Total" key is simultaneously locked against depression. The locking of the No. 1 "Total" key notifies the operator that the balance totalizer is in an overdrawn condition. At this time, the operator may pursue either of two courses. The No. 1 "Total" key may be manually unlocked and the balance operation continued, or the "Overdraft" key may be depressed to release the machine for an overdraft operation in which the complementary amount of the overdraft is transposed to a true negative amount and recorded. The overdraft mechanism used in the machine of this invention is basically the same as that illustrated and described in co-pending application for United States Letters Patent of Charles L. Lee, filed April 14, 1932, Serial No. 605,160, which issued on May 4, 1937, as patent No. 2,079,355. However, installation of the rotary drive shaft necessitated numerous changes in the overdraft mechanism in order to adapt it for use in the present machine. Therefore all the new mechanism and all the mechanism affected by the installation of the rotary drive shaft will now be described in detail and description of the overdraft mechanism not explained herein may be had by referring to the patent mentioned above.

Directing attention to Figs. 1, 2, 3, and 5, the "Overdraft" key 408 is composed of two parts, an upper part or stem 409 and a lower part or pitman 410. The stem 409 is slidably mounted by means of the upper end thereof, which extends through an opening in the auxiliary keyboard plate 90 and a slot in the lower end which fits loosely over a stud 411 secured in the frame 40. The pitman 410 is mounted to slide in harmony with the stem 409 by means of slots in said pitman in cooperation with the stud 411 and a stud 412 carried by an auxiliary plate 413 secured to the frame 40. The stem 409 is normally connected to the pitman 410 by means of a latch 414 pivotally connected to said stem and having an ear 415 which is urged into engagement with a notch in said pitman by means of a spring 416 which also urges the stem upwardly to normally maintain a shoulder thereof in contact with the lower surface of the plate 90. In case the overdraft key is inadvertently retained depressed at the end of an overdraft operation, mechanism presently to be described rocks the latch 414 counterclockwise to disengage the ear 415 from the pitman 410 to allow said pitman to return to normal position independently of the stem 409.

A spring 417 urges the pitman 410 upwardly to normally maintain an upward extension 418 thereof in contact with the lower surface of the plate 90. A link 419 is connected at its upper end to the pitman 410 and is slotted at its lower end to receive the stud 75 in the releasing lever 66.

When the No. 1 totalizer is not overdrawn, the overdraft key 408 is locked against depression. This is accomplished by means of a latch 420 (Figs. 8 and 9) loose on the stud 411, said latch having a notch in an upward extension thereof, which, in cooperation with a bent-over extension 421 of the pitman 410, blocks downward movement of said pitman. The latch 420 is connected by a link 422 to an arm 423 secured to an overdraft shaft 424 journaled in the totalizer frame 202. When an overdraft occurs, the shaft 424 is rocked a slight distance clockwise, which, by means of the arm 423 and link 422, imparts counterclockwise movement to the latch 420 to disengage the notch therein from the extension 421 to unlock the overdraft key. The manner in

which the overdraft shaft is restored counterclockwise to normal position will be explained later herein.

The overdraft shaft 424 (Figs. 16 and 18) has secured to its left end an arm 425 connected by a link 426 to pitman 427 which is in turn connected to the upper end of a latch 428 loose on a stud 429 in the frame 41. Movement imparted to the shaft 424, which is clockwise as viewed in Fig. 8 and counterclockwise as viewed in Figs. 16 and 18, by means of the arm 425, link 426, and pitman 427, rocks the latch 428 counterclockwise to cause a bent-over ear thereof to enter a notch in the stem of the No. 1 "Total" key to lock said key against depression when the balance totalizer is overdrawn.

The functioning of the balance totalizer and of the auxiliary differential is controlled in overdraft operations by means of a cluster of cams driven by means of a pinion 430 (Figs. 1, 2, and 5) secured to the shaft 53 and connected by a pinion 431 rotatably mounted on the plate 413 to an overdraft drive gear 432 loose on the stud 67 in the frame 40. The ratio between the gear 432 and the pinion 430 is such that one revolution of the shaft 53 in a counter-clockwise direction rotates the gear 432 one-third of a counterclockwise revolution. Secured to the gear 432 is a collar 434 (Figs. 5 and 7) with three equally spaced notches adapted to cooperate with the tooth 435 of a pawl 436 pivotally connected to a disk 437 assembled with a plurality of overdraft control cams which form a cluster 438 rotatably supported by the stud 67. It is therefore obvious that in overdraft operations which consist of three cycles of movement of the machine operating mechanism, the gear 432 will make one counter-clockwise revolution. The disk 437 and its associated cams are assisted to and maintained in home position by means of a lever 439 (Fig. 1) pivoted on the rod 123 and carrying a roller 440 which is urged into cooperation with a V-notch in the disk 437 by a spring 441.

When the "Overdraft" key 408 (Fig. 5) is in undepressed position, a camming surface on a projection 442 of the pitman 410 engages a tail 443 of the pawl 436 to maintain said pawl disengaged from the notches in the collar 434. Consequently, during regular machine operations the gear 432 and collar 434 rotate idly without imparting any movement to the cam cluster 438. Depressing the "Overdraft" key allows a spring 444, assisted by an angular extension 445 of the pitman 410, to rotate the pawl 436 counter-clockwise to engage its tooth 435 with one of the notches in the collar 434. Also, depression of the "Overdraft" key, by means of the link 419 (Fig. 3), rotates the release lever 66 to release the machine for operation in the manner previously explained.

In order to insure that the machine operates through three cycles in overdraft operations, the "Overdraft" key is retained depressed by locking mechanism presently to be described, and a finger 450 of the link 419 moves in the path of an abrupt surface 446 of the non-repeat latch 87 to prevent the functioning of said latch while the overdraft key is depressed.

Mechanism for locking the "Overdraft" key depressed consists of a latch 447 (Figs. 8 and 9) loose on the stud 411 and having a stud 460 to which is connected one end of a link 448. The other end of the link 448 is connected to a bell crank 449 loose on a rod 123, which also rotatably supports the lever 439 (Fig. 1). The bell

crank 449 carries a roller 451 adapted to co-operate with the periphery of a cam 452 which is a part of the cluster 438. A spring 453 urges the bell crank 449 clockwise, which, by means of the link 448, also urges the latch 447 clockwise to maintain a projection 454 thereof in contact with the inner surface of the extension 421 of the pitman 410. Depression of the "Overdraft" key 408 allows the latch 447 to hook over the top edge of the extension 421 to lock said "Overdraft" key depressed during overdraft operations. Near the end of an overdraft operation a node 455 of the cam 452, in cooperation with the roller 451, rocks the bell crank 449 counter-clockwise to disengage the latch 447 from the extension 421 to allow the overdraft key to be restored upwardly by the spring 417 (Fig. 5).

In case the overdraft key 408 (Figs. 8, 9, and 10) is retained depressed, the stud 460 engages an extension 461 of the latch 414 to rock said latch counter-clockwise to disconnect the finger piece or stem 409 from the pitman 410 to allow said pitman to return to normal position independently of said stem, as previously explained.

It will be recalled, by referring to Fig. 8, that an overdraft causes the overdraft shaft 424 to receive clockwise movement to unlock the "Overdraft" key. The manner in which the overdraft shaft is restored to normal position and the latch 420 is returned to locking position will now be described.

Turnably mounted on the latch 420 (Fig. 9) is a pawl 456 with a tooth 457 urged clockwise into communication with a similar tooth 458 on the latch 447, by a spring 459. Counter-clockwise releasing movement of the latch 447 causes the tooth 458 to move beyond the tooth 457; therefore, when the spring 453 (Fig. 8) returns the bell crank 449 and the latch 447 clockwise, the latch 420, by means of the pawl 456, moves in unison with said latch and, by means of the link 422 and arm 423, restores the overdraft shaft 424 counter-clockwise to normal position. The pawl 456 remains engaged with the tooth 458 until in a subsequent operation upward movement of the arm 412 (Figs. 8, 9, and 11) causes a stud 463 therein to engage a tail 464 of the pawl 456 to disengage said pawl from the tooth 458, leaving said parts in their normal positions, as shown in Fig. 9.

As previously stated, it is necessary to disable the printing mechanism during the first two cycles of overdraft operations in order to prevent complementary overdraft entries from being made upon the record material. The mechanism for accomplishing this result is shown in Figs. 8 and 11 and will now be described.

A link 465, the forward end of which is loose 60 on the stud 463, connects the link 412 to an upward extension of a lever 466 loose on the rod 123. The lever 466 carries rollers 467 and 468 which cooperate respectively with companion cams 469 and 470 which form an integral part 65 of the assembly 438 (see also Figs. 5 and 7). At the beginning of an overdraft operation, the cams 469 and 470 rock the lever 466 counter-clockwise, which, by means of the link 465, moves the link 412 clockwise to disengage the notch 70 therein from the stud 411 in the cam lever 410 and to engage another notch 471 in said link with a stationary stud 472 to secure the printing mechanism in ineffective or home position during the first and second cycles of an overdraft operation. At the beginning of the third cycle of an

overdraft operation, the cams 469 and 470 return 5 the lever 466 clockwise to reengage the link 412 with the stud 411 so that the printing mechanism will function to print the true negative amount of the overdraft.

Auxiliary differential

As previously stated, the machine of this invention has an auxiliary differential into which the complementary overdraft is temporarily transferred when the balance totalizer is cleared in the first cycle of an overdraft operation. In the second cycle of an overdraft operation, the cleared balance totalizer is selected for a subtract operation and the wheels of the auxiliary differential control the movement of the actuator racks 122 (Fig. 12) in their initial movement rearwardly, consequently the complementary amount of the overdraft is subtracted from the cleared No. 1 or balance totalizer. It is obvious that this results in the true negative amount of the overdraft being stored in the No. 1 totalizer.

Referring to Figs. 12, 14, and 15, the auxiliary differential has a wheel 473 for each denomination of the machine. Each of these wheels is adapted to cooperate with an auxiliary rack 474 secured to the corresponding denominational actuator rack 122. The auxiliary differential wheels 473 are loosely supported in a rockable frame 475, opposite ends of which terminate in arms 476 loosely mounted on the rod 123. Each of the arms 476 carries a roller 477 embraced by camming slots in two symmetrical arms 478 secured at opposite ends of the engaging shaft 63 journaled in the frames 40 and 41. Secured on the right-hand end of the shaft 63 is a crank 480 with a roller 481 adapted to cooperate with the periphery of a plate cam 482 which forms an integral part of the cluster 438, which, as previously stated, makes one counter-clockwise revolution each overdraft operation. Springs 483 connected to the arms 477 urge said arms and the shaft 63 clockwise to maintain the roller 481 in contact with the periphery of the cam 482.

Before explaining the manner in which the auxiliary differential functions, it will probably be advantageous to describe the mechanism which controls the functioning of the balance totalizer in overdraft operations.

Control of the balance totalizer in overdraft operations

Mechanism to control the functioning of the balance totalizer during overdraft operations will now be described.

Loose on the rod 123 (Fig. 10) is a bell crank 484 with a roller 485 which is urged by a spring 487 into communication with the periphery of a cam 486 assembled with the cluster 438. The bell crank 484 is connected by a link 488 to a crank 489 secured on the righthand end of a control shaft 493 journaled in the frames 40 and 41. Secured on the lefthand end of the shaft 493 (Figs. 10, 17, and 18) is an arm 494 with a stud 495 embraced by the bifurcated end of a link 496, the rearward end of which is connected to a downward extension on the No. 1 control lever 360. The stud 495 (see also Fig. 16) is embraced by the hook-shaped forward end of a subtract control link 497, the rearward end of which is connected to an upward extension of the subtract control arm 301. The stud 495 is likewise embraced by the hook-shaped forward end of an add control link 498 similar to the link 497, the rearward end of said link 498 being connected to a

No. 2 add control arm 499 which controls the adding function of the No. 2 totalizer in exactly the same manner as the arm 186 (Fig. 16) controls this function in the No. 4 totalizer.

5 In the beginning of the first cycle of an overdraft operation, counter-clockwise movement of the cam 486 (Fig. 10) allows the spring 481 to rock the bell crank 484 clockwise, which, by means of the link 488, rocks the shaft 493 and the arm 494 also clockwise as here viewed and counter-clockwise as viewed in Figs. 16, 17, and 18. This movement of the arm 494, by means of the link 496, rocks the lever 360 clockwise as viewed in Fig. 17 to move the pitman 322 (Fig. 18) upwardly into engagement with the stud 346 in the engaging plate 338 to engage the No. 1 totalizer for a clearing operation in exactly the same manner as explained for the No. 4 totalizer.

Clockwise movement of the engaging plate 338 engages the wheels of the No. 1 totalizer with the actuator racks 122 (Fig. 12) prior to their initial movement rearwardly. Initial movement of the racks 12 rotates the No. 1 totalizer wheels reversely to zero to position said actuator rack commensurate with the amount thereon. Upon completion of the rearward movement of the racks 122, the wheels 473 of the auxiliary differential 475 are moved into engagement with their corresponding auxiliary racks 474. This is accomplished by means of the cam 482 (Figs. 14 and 15), counter-clockwise movement of which, in cooperation with the roller 481, rocks the arm 480, shaft 63, and engaging arm 478 counter-clockwise. The configuration of the cam slots in the arms 478, in cooperation with the rollers 477, rocks the auxiliary differential upwardly or counter-clockwise to engage the wheels 473 with the auxiliary racks 474. The wheels of the auxiliary differential have positive stops which locate them in zero position, and these wheels are always standing at zero prior to their engagement with the auxiliary racks 474. After the wheels of the No. 1 or balance totalizer have been turned to zero by initial movement of the racks 122, return movement of the plate 338 disengages said totalizer wheels from said actuator racks. Return movement forwardly of the racks 122 in the latter part of the first cycle of an overdraft operation rotates the auxiliary differential wheels 473 to transfer the complementary amount of the overdraft from the No. 1 totalizer to the auxiliary differential.

Due to the fact that the detent 358 (Fig. 17) and the No. 1 "Total" key receive no movement in overdraft operations, it is necessary to employ a link 500 loose on the stud 359 in the lever 360 and bifurcated to receive the stud 389 in the bell crank 393 so that clockwise movement of the lever 360 will be transmitted to the bell crank 393 to move the stud 395 into the path of the lever 400 to cause any depressed amount keys to be released at the beginning of an overdraft operation. Further details of the releasing mechanism may be found in the parent case.

65 By observing Fig. 10 it will be understood that the shaft 493 and associated parts have three positions, a neutral or home position in which said parts are here shown, a rearward or clockwise position to select the balance totalizer for clearing operations, and a forward or counter-clockwise position to which a raised portion 501 of the cam 486 rocks said parts in the beginning of the second cycle of an overdraft operation. This shifts the links 497 and 498 forwardly (Figs. 16 and 18) to rock the subtract control arm 301 for

the balance totalizer and the add control arm 499 for the No. 2 totalizer to respectively select said totalizers for subtract and adding operations.

In the second cycle of an overdraft operation, 5 initial movement rearwardly of the actuator racks 122 rotates the wheels of the auxiliary differential, which are still engaged with the auxiliary racks 474, back to zero position. It is apparent that at this time the auxiliary differential 10 controls the positioning of the actuator racks 122. Therefore, the complementary amount of the overdraft which was stored in the auxiliary differential will be subtracted from the cleared balance totalizer and simultaneously added in the 15 No. 2 totalizer. It is therefore clear that at the end of the second cycle of an overdraft operation, the true negative amount of the overdraft will remain in the balance totalizer. Prior to return movement forwardly of the actuator racks 20 122, the wheels of the auxiliary differential, which are now standing at zero, are disengaged therefrom.

It is to be understood that the adding of the 25 complementary amount of the overdraft during the second cycle of an overdraft operation is not limited to the No. 2 totalizer, but this amount may be added into any one or as many of the totalizers as desired. This may be accomplished by connecting the link 498 (Fig. 18) to the desired add control arm or arms.

A link 501 (Figs. 10 and 16) is hook-shaped on both ends to fit over a stud 502 in the arm 494 and the stud 389 in the bell crank 393. This link provides a means of transmitting the clockwise movement of the arm 494 as observed in Fig. 16 to the bell crank 393 to cause any depressed amount key to be released at the beginning of the second cycle of an overdraft operation.

In the third cycle of an overdraft operation the cam 486 (Fig. 10) again selects the No. 1 or balance totalizer for a clearing operation. It will be recalled that the mechanism illustrated in Fig. 11 connects the printer actuating mechanism to its operating lever 110 at the beginning of the third cycle of operation. Therefore, in this final cycle of an overdraft operation, the No. 1 or balance totalizer is cleared and the true negative amount of the overdraft is printed upon the record material.

It is felt that a clear understanding of the operation of the machine will have been obtained from the preceding specification, and for this reason no description of operation in connection 55 with a particular business system has been included herein. However, the machine of the present invention is very flexible in nature and may, with minor adjustments and changes, be adapted for use in the majority of present-day businesses. 60

While the form of mechanism herein shown and described is admirably adapted to fulfill the objects primarily stated, it is to be understood that it is not intended to confine the invention to the one form or embodiment herein disclosed, for it 65 is susceptible of embodiment in various forms, all coming within the scope of the claims which follow.

What is claimed is:

1. In a machine of the class described, adapted 70 to perform regular and overdraft operations, the combination of an overdraft control member comprising two elements adapted to move in unison to release the machine for an overdraft operation; a latch connecting the elements; means to retain 75

the control member in moved position during overdraft operations; means to release the retaining means near the end of an overdraft operation; and means whereby the releasing means 5 disengages the latch when one of the elements is retained in moved position to allow the other element to be restored to normal position.

2. In a machine of the class described adapted to perform regular and overdraft operations, the 10 combination of an overdraft control member; a separate fingerpiece for the member; a latch to normally connect the fingerpiece to the member; means to retain the control member in moved position during overdraft operations; and means 15 to release the retaining means near the end of an overdraft operation, said releasing means in cooperation with the retaining means also adapted to disengage the latch when the fingerpiece is held down to allow the control member to return 20 to normal position.

3. In a machine operable to perform plural cycle overdraft operations, the combination of an overdraft key; a cycle controller operable to control the operation of the machine in overdraft operations; a gear operable to make a complete rotation during the plural cycles of an overdraft operation; and clutch mechanism rendered operable by said overdraft key each time the key is operated, for coupling the cycle controller 25 to the gear for operation thereby.

4. In a machine of the class described having totalizers, totalizer engaging mechanism, differential mechanism, storage devices, and printing mechanism, the combination of a rotatable main 30 shaft having means thereon to operate the totalizer engaging means, the differential mechanism, and the printing means; a cycle control mechanism operable to selectively control the operation of the totalizer, printing means, and storage de- 35

vices during a plurality of cycles of an overdraft operation; means for driving the cycle controller including a gear operable to make one complete rotation during the plural cycles of an overdraft position and a gear on the rotatable main drive shaft for driving the first mentioned gear; and means for rotating the main drive shaft. 5

5. In a machine of the class described operable in single cycle operations and plural cycle overdraft operations and having a totalizer, totalizer engaging mechanism, differential mechanism, a storage device, and printing mechanism, the combination of a rotary drive shaft having means thereon to operate the totalizer engaging means, 10 the differential means, and the printing means; control mechanism operable to selectively control the operation of the totalizer engaging means, the printing means, and the storage device in true negative total printing operations; and means 15 on the rotary drive shaft for operating the control mechanism in true negative total operations. 20

6. In a machine of the class described, a rotatable drive shaft; a control means operable during three cycles in overdraft operations; means for driving the control means including a gear on the drive shaft and a second gear meshing therewith operable one third of a revolution for each rotation of the first gear; a disk fast to the second gear and having three equispaced 25 notches in its periphery; a pawl pivoted on the control means and operable to engage the notches in the disk to connect the control means to the second gear for operation thereby; and an overdraft key for controlling the operation of the 30 pawl. 35

LEEFE JANE LEE,
